UNITED STATES PATENT OFFICE.

ROBERT W. SCOTT, OF BABYLON, NEW YORK, ASSIGNOR TO SCOTT & WILLIAMS, INCORPORATED, A CORPORATION OF MASSACHUSETTS.

WEB-HOLDER MECHANISM FOR KNITTING-MACHINES.

1,345,408.

Specification of Letters Patent.

Patented July 6, 1920.

Original application filed December 31, 1914, Serial No. 879,887. Divided and this application filed September 30, 1919. Serial No. 327,392.

To all whom it may concern:

Be it known that I, ROBERT W. SCOTT, a citizen of the United States, and resident of Babylon, in the county of Suffolk and State of New York, have invented new and useful Improvements in Web-Holder Mechanism for Knitting-Machines, of which the following is a specification.

This invention relates to improvements in web-holder mechanism for knitting machines, and more particularly relates to web-holder mechanism adapted to be made operative or inoperative, for instance in response to the automatic indications of pattern mechanism controlling the operations of the machine.

Heretofore, so far as I am aware, knitting machines provided with movable web-holders have included actuating devices for the web-holders always in operative contact with or in positive controlling relation to the web-holders, whether the purpose of the devices is to cause motion of the web-holders, or is to maintain the web-holders inactive at one or another part of the path of motion given the web-holders when actuated. Such operation of the web-holders is prohibitive of useful function for the web-holders and detrimental to the fabric produced in certain types of knitting machinery, and its employment sets limitations upon the uses of, or dictates undesirable constructions or operations of, other agencies of the machine. I have therefore devised new web-holder mechanism well adapted to use in knitting machinery for many desirable purposes, for instance to begin or to end actuation of the web-holders in coördination with the beginning and ending of a coöperative movement of the needles or other parts of the machine. In connection with the beginning or ending of actuation of the needles and other parts upon commencing to knit (as when establishing or ceasing to knit at an additional knitting wave) the particular character of the beginning and ending phases of the motion of the web-holders is of great importance to correct and certain function of the knitting instruments. This invention provides new mechanism for the actuation and automatic cessation and resumption of actuation of web-holders. I shall describe the invention in connection

with one particular species adapted to use in a machine for knitting both single-course and double or multiple-course fabrics, including relatively complete articles of hosiery such as stockings having integral welts, mock-rib tops, and seamless legs, heels and toes, the particular machine shown being adapted to make at desired parts of the fabric sections of mock-rib or accordion, tucked or other multiple-course fabric of well-known old structure, and being described and claimed in my copending application for Letters Patent of the United States Serial No. 879,887 filed December 31, 1914, of which this application is a division, now Patent No. 1,317,897, Oct. 7, 1919. But it will be understood that the invention is independent of the particular machine chosen to illustrate one species of the genus comprising the invention and herein claimed.

In the accompanying drawings,

Figure 1 is a fragmentary right side elevation of a circular machine provided with the web-holder mechanism;

Fig. 2 is a plan illustrating the parts shown in Fig. 1;

Fig. 3 is an under plan of the web-holder cap ring;

Figs. 4 and 5 are sections on the line 4—4 of Fig. 3, illustrating two different positions of the auxiliary web-holder cam;

Figs. 6, 7 and 8 are detailed elevations of web-holders having butts of three different lengths;

Fig. 9 is a detail illustrating a modification of the web-holders and auxiliary web-holder cam; and

Fig. 10 is an under plan of an auxiliary advancing cam for the web-holders.

Referring to the drawings, the machine may be of the general type illustrated by my prior Letters Patent No. 1,152,850 dated September 7, 1915, and No. 1,148,055 dated July 27, 1915. Such a machine comprises a rotary needle cylinder 260 and reciprocatory knitting needles therein, means to support and drive the needle cylinder, and automatic ancillary devices including a pattern drum or other surface 120 occasionally moved at times determined by a primary pattern mechanism in time with the passage past a given point of a particular segment of the cylinder 260, indications on this surface

being employed to actuate instrumentalities of the machine. Cams placed on the drum 120 may be employed to operate instruments coöperating with the needle cylinder 5 by transmitting their indications to thrust-bars 460, for instance, mounted and operating as explained in my said Letters Patent.

The needle cylinder may carry the usual long-butts series and the usual short-butts 10 series of knitting needles, for operation as explained in my said application Serial No. 879,887, by cams including an auxiliary knitting cam mounted on a slide 2, Fig. 2 for movement radially of the needle-cylinder 15 into and out of contact with the butts of the needles, as determined by the position of a lever 20 coöperating with a cam 26^a on a thrust-bar 26 worked by suitable cams 517 on drum 120.

20 Upon standard 401 at the rear of the machine the usual latch-guard ring 550 may be pivoted at 552, to rest when in operation on the standard 400 at the front of the machine. A main yarn-feeding and yarn- 25 changing mechanism may comprise yarn changing fingers F pivoted at 554 on the latch-ring, in position for operation by some of the thrust-bars 460, for instance as fully explained in my Letters Patent No. 1,238,052 30 dated August 21, 1917.

The needle cylinder 260 carries an attached web-holder bed 295, Figs. 1, 4 and 5, which may be the same as that of my said 35 patents.

35 A web-holder cam cap 300 is mounted for free rotation on an annular shoulder of said bed 295, said cap being held stationary in each direction by one of the adjustment screws 303 in lugs 304 straddling the standard 400, as usual.

40 On said cam cap, to coöperate with the needles and the main knitting cams as explained in my said patent No. 1,152,850, an out-throw cam 306 and adjustable in-throw 45 cams 309 are provided in coöperation with the independently movable web-holders 292 carried in radial grooves in the bed 295. The machine may also be provided with an automatically adjustable cam 312 for shifting 50 the time of actuation of the web-holders 292 having long butts 29 at the region of the main stitch cams. Cam cap 300 is provided with a concentric groove 305 for maintaining the web-holders, except as described 55 below, in their advanced position.

The machine is provided with suitable devices for lifting or advancing all of the needles intended to coöperate with the auxiliary knitting cam carried by the slide 60 2 to knit at their down stroke given by this cam, and may be provided with an auxiliary cam or cams for depressing or otherwise positioning needles not to be operated by said auxiliary cam, as fully explained in my 65 said parent application Serial No. 879,887.

The arrangement may be such that the machine will normally knit a plain tubular single-course fabric by means of its usual cams from the usual main yarn-feed at one of the fingers F, and it may be capable, upon 70 suitable actuation of the slide 2, of then establishing and feeding one or more other waves, for instance to form a stocking top of accordion fabric. When this or any similar 75 operation is to be carried out, it is important that the machine should be capable of being adjusted to knit single-course or to knit double-course without disturbance of the device for knitting the plain single-course parts of the article, or of the function 80 of the devices for the usual stocking knitting purposes.

For the purposes suggested it is particularly desirable to cause the web-holders 292 to coöperate with the supplemental stitch 85 cam, or with the intervening needles affected by other cams coöperating with this cam during the knitting of the double course mock-rib or accordion fabric. To avoid stretching and wear upon retained loops due 90 to withdrawing and inserting the web-holders in the absence of the auxiliary knitting wave, and other objections to moving the web-holders during single-course knitting, it is desirable to restore the web-holders 95 to their normal operating path during the periods of inaction of the auxiliary cams.

For the making of such articles, having predetermined sections of plain single course fabric and double course fabric of any kind, 100 it is also necessary to feed a yarn in proper relation to the knitting wave formed at the supplemental stitch cams. Means for feeding an auxiliary yarn *x* to the auxiliary or second wave in the needles may comprise 105 a guide 51 for the auxiliary yarn mounted on the end of a lever 50 overhanging the latch ring 550 and pivoted at 554 on the same axis as the pivoted yarn-fingers F for the main yarns *y*, the parts at 110 the latch-ring being suitably recessed to permit guide 51 to come into operative relation to needles advanced to take yarn from it, as explained more at length in my said parent application Serial No. 879,887 and claimed 115 in my copending divisional application Serial No. 327,393, of even date herewith.

The auxiliary yarn guide lever 50 is lowered to its operative position and elevated to its inoperative position by an actuating 120 lever 70 pivoted on an extension of the latch ring pivot 552, said lever 70 having an enlargement 71 taking over the bent upper end of thrust bar 26, and said lever also being provided with a shoulder 72 taking under a 125 flat on said lever 50. Lever 70 terminates in a boss 74 bored to receive a spring plunger 75.

Mounted on cap ring 300, as by pivoting on an elongated abutment screw 303 in one 130

of the lugs 304 a lever 85 extends above the part of the periphery of the cam cap 300 lying toward the observer in Fig. 1. Lever 85 terminates at 86 in a flat upon which plunger 75 rests, is normally maintained in an elevated position by a spring plunger carried in nipple 87, and is held on its pivot 303 by collar 84.

Lever 70 is rotated on stud 552 to elevate auxiliary yarn guide lever 50 and to permit lever 85 to be elevated by its spring plunger, for instance by a relatively strong spring 73 attached to said lever 70 at one end and to a limit screw 22 carried by bracket 21 at its other end, whenever cams 517 on drum 120 permit thrust bar 26 to be lowered.

Referring now to Figs. 3, 4 and 5, an auxiliary withdrawing cam 88 for the web-holders 292 is carried by the lever 85 for substantially vertical movement about the pivot 303 as a center. Said cam may comprise a plate adjustably fastened by screws 89 on the upper surface of lever 85, said plate having a downward extension cam 25 shaped at its working end substantially as shown in Fig. 3, and capable when lever 85 is depressed of entering a cut 90 formed through web-holder cam cap 300 to stand across concentric groove 305 at the proper 30 point in relation to the needles elevated to knit at the auxiliary cam on slide 2.

For durability of construction and accuracy of operation I prefer to build up the cam cap 300 as illustrated in Figs. 3, 4 and 5 of a separate incomplete shouldered annulus 301, which may be of hardened steel, sprung in place to form the inner margin of groove 305, the main body of said ring 300 comprising a casting having lugs 304 and enlargements 317, and a turned flat on its under side to form the floor of the groove 305, a turned depending outer flange 318 providing a running bearing upon the shouldered web-holder bed 295.

The main web-holder withdrawing cam 306 is provided with beveled ends, and may be fastened to cap 300 by screws 319, thus filling the gap formed in ring 301, which is cut away on a chord of the circle defined by it, in such a manner as to leave no sharp edges at the meeting-points of cam and ring to cause breakage of web-holder butts. Ring 301 determines the inmost position of the web-holders, and the described construction, 55 enabling it to be hardened as a protection against the rebound of the web-holder butts, and enabling easy removal and assembly, is of importance to the operation of the machine.

A flattened portion of ring 301, as at 320, 60 may be provided to permit cam 88 to stand across the circular path of the web-holder butts. The opening 90 for the movement of cam 88 may be formed as an open depression in the inner face of cap 300, as shown,

ring 301 when in place closing the inner part of said opening. Outward movement of web-holder butts by the cam 88 is permitted by enlargement 92 of the outer periphery of groove 305, which enlargement 70 may be defined by an adjustable cam 91 housed in a horizontal slot 93 formed through the enlargement 317 of cap 300, in which slot said cam 91 is frictionally held in its adjusted position by countersunk 75 pinch screws 94 taking into enlarged bores 96 (Fig. 10) in said cam 91, one end of which is an adjustable advancing cam for movement of the web-holders 292 inward to their normal concentric path 305. This path 80 is such as to cause the web-holders to project between the needles, to maintain the yarn under a sufficient tension against the shanks of the needles.

The relative position of the wave formed 85 by the web-holder cam 88 and the wave formed by the auxiliary needle operating devices is such as to maintain said web-holders forward to hold down the web during the advance of the needles, and to reinsert said web-holders prior to, at or near the most depressed position of the needles due to the auxiliary cams, thereby again advancing the web-holders prior to rise of the needles at or preceding the main knitting 95 wave, and thus to secure the passage behind the advancing needles which have not taken yarn α at the supplemental yarn feed of the floats or sinker wales of said yarn α .

For automatic operation, it is desirable 100 to move the cam slide 2, when the auxiliary wave is to be formed in the needles, in two or more stages, the first taking place during the passage of the short butt needles and the second taking place after the leading long 105 butt needles have passed down the face of the cams carried by said slide. This is secured by suitable steps 517* on the cam 517.

As more fully described in my said patents, it is desirable to operate some of the 110 web-holders at cam 312, for instance those associated with the short butt needles, so as to draw longer stitches locally, and for this purpose said web-holders are provided with long butts as illustrated at 29 in Fig. 111, 6, the remaining web-holders being provided with short butts as at 28, Fig. 3.

The first movement of bar 26, lever 70, and lever 85 will therefore occur during passage at the auxiliary stitch cams of 120 needles having short butts and of web-holders having long butts, but it is desirable at this time to establish the auxiliary wave in the web-holders, and for this purpose the cam 88 must enter upon the series of web-holders traveling in the concentric groove 305. This can not be done with respect to the unbroken series of long butt web-holders 29, and I therefore provide among said long butt web-holders certain having intermediate 125 130

butts 27, Fig. 10, upon which the said cam 88 may enter to first operatively encounter and move outward a web-holder having a long butt 29 following the series 27.

5 An alternative structure for this purpose is illustrated in Fig. 9, showing a cam 88^a having a beveled operative face and a web-holder having a butt 29^a beveled on the side toward the center of the needle carrier, so 10 that movement of the cam transversely to the path of the web-holder butts will force enough of them outwardly to permit the cam to enter its final operative position.

It will now be understood without further 15 description that the operation of thrust bar 26 secures entrance of the auxiliary yarn guide, entrance of the auxiliary stitch cam, of the auxiliary supplemental cam, and entrance of the auxiliary web-holder cam 88. 20 The devices described accomplish the movement of said web-holders, beginning at a predetermined point, through their full retraction and advance without moving any of them to an intermediate position only.

25 The exit of the auxiliary web-holder cam 88 occurs during the passage of the short butt needles and preferably at that section of the web-holders provided with the medium butts 28 placed among web-holders having 30 the long butts 29 associated with the short butt segment of the needles. But the cam 88 may be withdrawn in any position without displacing the web-holders, the in-throw cam 91 moving all the web-holders in to 35 their normal concentric position. It will be observed that the actuating lever 70 does not positively move either lever 50 to introduce the yarn or lever 85 to enter the web-holder cam, movement of said actuated parts 40 being due to spring 53 and spring plunger 75, whereby accidents of timing will not cause breakage of parts.

It will be observed that the devices for 45 actuating the web-holders as above described provide for the automatic beginning and the automatic ending of a wave of motion in the web-holders characterized by fully retracting the first web-holder encountered by the cam 88, the next preceding web-holder 50 remaining in its normal concentric path. Unless this function were secured, the first needles to be advanced and retracted by the devices on slide 2 for causing the auxiliary needle-wave would encounter some web-holder in an intermediate position. If any 55 of the web-holders were then held rigidly in an intermediate or advanced position, the retracting needles of the newly-established wave would either break the yarn α or draw 60 abnormally long loops against the hooked tops of the web-holders. The advancing movement of the needles could also, if any 65 of the web-holders were left, at the end of their actuation, for instance, in an incorrect withdrawn position, result in causing the

fabric-loops to ride above the web-holder hooks, so that the needles could not cast off at the next succeeding knitting wave. Breakage of machine parts as well as damage to the product is thus avoided. The 70 described devices for operating the web-holders not only prevent, in the illustrative application to a particular type of machine, these occurrences, but they constitute a simple and reliable construction adapted to be 75 applied without change and with little effort and expense to other machines of the same or other types, there to secure the same advantages.

What I claim is:

1. A knitting machine having in combination needles, knitting cams, movable web-holders, a web-holder cam-cap, and a web-holder actuating cam mounted on said cam-cap for movement into and out of contact 85 with said web-holders in a direction transverse to the path of operative movement of said web-holders.

2. A web-holder mechanism for knitting machines comprising an apertured cam-cap, 90 and a web-holder withdrawing cam movable through said aperture into and out of contact with said web-holders.

3. A web-holder cam-cap for knitting machines having a circular web-holder groove 95 therein and having a withdrawing cam thereon movable transversely to the plane defined by said circular groove.

4. A web-holder mechanism for knitting machines having therein means for supporting a series of web-holders having operating butts and means for operating the web-holders comprising a cam for advancing and a cam for withdrawing the web-holders, means to support one of said cams for motion into and out of the path of motion of the web-holder butts, and means for moving said last named supporting means. 100

5. A web-holder mechanism for knitting machines having therein means for supporting a series of web-holders having operating butts, means for operating the web-holders comprising a withdrawing cam and means for supporting said cam for motion into and out of contact with the operating butts of 115 the web-holders.

6. A web-holder mechanism for knitting machines having therein means for supporting a series of web-holders having operating butts of different lengths, and means for operating the web-holders comprising a cam for advancing and a cam for withdrawing the web-holders, means to support one of said cams for motion into and out of the path of motion of the web-holder butts, and 120 means for moving said support to first engage the cam with the longer butts.

7. A web-holder mechanism for knitting machines having therein means for supporting a series of web-holders having operating 125

- butts, means for operating the web-holders comprising a withdrawing cam and means for supporting said cam for motion into and out of contact with the operating butts of the web-holders, and means for moving the support in stages, first to engage the longer and thereafter to engage any of the operating butts. 8. Web-holder mechanism for knitting machines having a rotary needle cylinder and a rotating web-holder bed attached to the needle cylinder having therein movable web-holders, comprising a cap having thereon cams for actuating the web-holders, one of said cams having a mounting movable transversely of the direction of motion of the web-holders, and means for moving the mounting at predetermined times whereby to introduce into and withdraw the cam from operative contact with the web-holders. 9. Web-holder mechanism for knitting machines having a rotary needle cylinder and a rotating web-holder bed attached to the needle cylinder having therein movable web-holders, comprising a cap having thereon cams for actuating the web-holders, one of said cams having a mounting movable transversely of the direction of motion of the web-holders, and means comprising a pattern surface, indications on the surface, and connections operated thereby for moving the mounting at predetermined times whereby to introduce into and withdraw the cam from operative contact with the web-holders. 10. A knitting machine having therein, in combination with the machine frame, the needle-cylinder, the web-holder bed, a series of web-holders carried by the bed, and a cam-cap, the cam-cap and bed being relatively revoluble, actuating means for the web-holders comprising a mounting movable on the cam-cap in a direction transverse to the relative direction of motion of the web-holders, a cam for actuating said web-holders carried by said mounting, and means mounted on the machine frame for positioning said mounting and actuating cam. 11. A knitting machine having therein, in combination, yarn feeding means including a yarn-guide movable into and out of operative relation to the needles; web-holder actuating mechanism including a cam movable into and out of operative relation to web-holders; a pattern-surface, and means between said pattern surface and said yarn-feeding and web-holder actuating mechanism for simultaneously moving them into and out of operative position. 12. A knitting machine having therein, in combination, yarn feeding means including a yarn-guide pivoted to swing down into and up out of operative relation to the needles; web-holder actuating mechanism including a lever and cam pivoted to swing down into 65 and up out of operative relation to web-holders; a pattern-surface, and means between said pattern surface and said yarn-feeding and web-holder actuating mechanism including a lever for simultaneously 70 swinging said yarn-guide and web-holder cam up and down. 13. A web-holder cam-cap for use in knitting machines comprising a track or way for the web-holder butts, a movable cam-mounting attached to the cap for movement transversely to the plane of said track or way, and a web-holder actuating cam mounted on said cam-mounting for entrance into and withdrawal from said track or way. 14. A web-holder mechanism comprising a series of web-holders, their carrier, and a cam-cap having therein a track or way for web-holder butts, and having an aperture exposing said butts, a mounting on the cam-cap, a cam on the mounting adapted in one position of the mounting to enter said aperture, means tending to move the cam out of contact with the butts, and pattern controlled means for moving the mounting to 80 engage the cam with the butts. 15. A web-holder mechanism comprising a series of web-holders having therein a segment having butts differing from butts of the remainder of the series, their carrier, and a cam-cap having therein a track or way for web-holder butts, and having an aperture exposing said butts, a mounting on the cam-cap, a cam on the mounting adapted in one position of the mounting to enter said aperture, means tending to move the cam out of contact with the butts, and means for moving the mounting at predetermined times during the passage of said segment of the web-holder butts, whereby to engage the cam 95 with the butts of the remainder of the web-holders. 16. A web-holder cam-cap for knitting machines having abutments to determine its rotative position in relation to parts to be 100 operated by it, a cam for operating the parts, and a lever pivoted on the cap in relation to one of the abutments and supporting the cam for motion into and out of operative position. 17. A web-holder cam-cap made as an annulus having a bearing-flange and a central opening, and having an aperture through the floor of a groove defined between said flange and the remainder of the cap, an internal ring forming another wall of the groove in the cap, and having mounted thereon a web-holder actuating cam movable into and out of said aperture. Signed by me at New York, N. Y., this 125 29th day of September, 1919.

ROBERT W. SCOTT,
